FUSED ELECTRIC CONNECTOR

Max J. Marcus, New York, N. Y.

Application January 14, 1952, Serial No. 266,277

15 Claims. (Cl. 200—115.5)

1

This invention relates to new and useful improvements in fused electric connectors and receptacles.

More specifically, the present invention proposes certain improvements in that type of fused electric receptacles which removably encloses a pair of cartridge type fuses for providing complete protection for the electric appliance or device with which it is connected and which will completely eliminate the danger of fire resulting from faulty electrical equipment.

As a further object, it is the primary purpose of the present invention to construct the fused electric receptacle so that it will have a pair of plug-in bars extended from its one end for insertion into a conventional electric outlet receptacle with a pair of openings at its other end associated with a pair of conductor members in a manner so that when the plug-in bars of a conventional plug attached to the cord of an electric appliance or device are inserted into the openings good electrical contact will be made with the conductor members to supply the current required to operate the appliance or device and at the same time the contained fuses will protect the appliance or device.

Another object of the present invention proposes constructing the fused electric receptacle to include a hollow body formed with an internal rib which divides off spaced channels within the body into which cartridge fuses are inserted in a manner to make electrical contact with spring clips mounted within the channels at the ends thereof.

As a further object, the present invention proposes openings in the one end of the body in alignment with the channels through which the fuses can be passed into electrical contact with the clips and holes in the other end of the body in alignment with the channels in a manner so that an elongated pusher member can be inserted through the holes for applying pressure to the fuses pushing them from the clips and out of the hollow body through the openings.

The present invention further proposes forming the clips at the end of the channels adjacent the holes with conductor strips projected into recesses formed in the rib inward of the respective clips in a manner so that when the plug-in bars of the conventional plug are inserted into the hollow body they will make electrical contact with said conductor strips.

As a still further object, the present invention proposes providing means within the hollow body for causing the conductor strips to be continually resiliently turned in a direction to bear rigidly against the plug-in bars of the plug in a manner to insure good electrical contact between the conductor strips and the plug-in bars of the plug.

Still another object of the present invention proposes arranging the turning means in such a manner that the act of turning the conductor strips to make good electrical contact with the plug-in bars of the plug will also cause the re-

2

spective clips to be held in concentric alignment within the respective channels to always be in position to receive the ends of the fuses when being inserted into position within the hollow body.

A further object of the present invention proposes constructing fused receptacles in several different ways to be used between the outlet receptacles and the plugs of electrical appliances or devices or to be mounted on the ends of extension cords in a manner to provide complete protection for the electrical appliances or devices which draw their electricity from the extension cords.

15 For further comprehension of the invention, and of the objects and advantages thereof, reference will be had to the following description and accompanying drawing, and to the appended claims in which the various novel features of the invention are more particularly set forth.

On the accompanying drawings forming a material part of the present disclosure:

Fig. 1 is a perspective view of a fused receptacle constructed in accordance with the present invention.

Fig. 2 is an enlarged elevational view of the fused receptacle with the one side removed and with one of the cartridge fuses shown in a partially removed position.

30 Fig. 3 is an inside elevational view of one of the halves of the hollow body of the receptacle.

Fig. 4 is an enlarged longitudinal sectional view taken on the line 4—4 of Fig. 1.

Fig. 5 is a perspective view of one of the clips used in the form of the invention shown in Figs. 1 to 4.

Fig. 6 is a developed view of the blank used for forming the clip shown in Fig. 5.

Fig. 7 is a perspective view of the other of the 40 clips used in the form of the invention shown in Figs. 1 to 4.

Fig. 8 is a perspective view of the anchor plate used in the form of the invention shown in Figs. 1 to 4.

Fig. 9 is a view similar to Fig. 2, but illustrating the receptacle constructed in accordance with a modification of the present invention.

Fig. 10 is an inside elevational view of one of the halves of the hollow body of the form of the invention shown in Fig. 9.

50 Fig. 11 is a longitudinal sectional view of the receptacle shown in Fig. 9.

Fig. 12 is a view similar to Fig. 1, but illustrating the receptacle constructed in accordance with a modification of the present invention.

Fig. 13 is an elevational view of Fig. 12 with one-half of the receptacle body removed.

Fig. 14 is an inside elevational view of one of the halves of the receptacle body of the form of the invention shown in Figs. 12 and 13.

Fig. 15 is another view similar to Fig. 1, but showing the receptacle constructed in accordance with a modification of the invention.

Fig. 16 is an elevational view of Fig. 15 with one-half of the receptacle body removed.

Fig. 17 is an inside elevational view of one of the halves of the receptacle body of the form of the invention shown in Figs. 15 and 16.

Fig. 18 is still another view similar to Fig. 1 illustrating the receptacle constructed in accordance with a further modification of the present invention.

Fig. 19 is an elevational view of Fig. 18 with one-half of the receptacle body removed.

Fig. 20 is an inside elevational view of one of the halves of the receptacle body of the form of the invention shown in Figs. 18 and 19.

The fused receptacle, according to the first form of the present invention illustrated in Figs. 1 to 8, includes a hollow body 30. The hollow body 30 is comprised of opposed halves 30^a, molded of any suitable dielectric material such as hard rubber. However, the body halves 30^a are preferably molded of one of the synthetic resinous materials having good dielectric properties. Each of the body halves 30^a is semi-elliptical in cross-section so that the body 30, when the halves are brought together, will be elliptical in cross-section, as can be best seen from Fig. 1. The ends of each of the body halves are closed by thin integral walls 31 and 32 which have meeting edges when the body halves are brought together.

Internally, the body halves 30^a are formed with narrow ribs 33 which are in alignment with each other and which extend at right angles to the end walls 31 and 32. The ribs 33 are located mid-way between the sides of the body halves 30^a and divide off spaced channels 34 for a purpose which will be explained as this specification proceeds. Each of the body halves 30^a has an aperture 35 extended through its rib 33. When the body halves 30^a are properly brought together, as shown in Fig. 4, the apertures 35 will be aligned for the passage of a nut and bolt assembly 36 which holds the body halves together as a unit. The outer ends of the apertures 35 are counter sunk to receive the head and the nut of the nut and bolt assembly so that the outer faces of the body halves remain flush.

The outer faces of the body halves 30^a removed from the apertures 35, are formed with inwardly sloped cavities 37 bounded on their deepest sides by outwardly directed ridges 38. The cavities 37 and the ridges 38 combine to provide convenient finger grips for pulling the fused receptacle out of a conventional electric outlet receptacle, as will become clear as this specification proceeds.

The channels 34, previously referred to, are in alignment when the body halves 30^a are brought together and house cartridge type fuses 39. As is generally known in the art, the amperage of the fuses 39 used in the receptacle will be governed by the wattage of the electrical appliance or device with which the receptacle is used. Positioned in the ends of the channels adjacent the end walls 31, there is a pair of like clips 40 which are engaged about the adjacent ends of the fuses 39. Positioned in the ends of the channels 34 adjacent the end walls 32, there is another pair of like clips 41 which are engaged about the other ends of the fuses 39. The clips 40 and 41 are resilient in construction so as to tightly grip the ends of the fuses and make good electrical contact therewith.

The end walls 32, in alignment with the ends of the channels 34, are formed with semi-circu-

lar notches 42. When the body halves 30^a are brought together, the notches 42 combine to form circular openings of a diameter to pass the fuses 39. The fuses 39 are inserted into the body through the circular openings formed by the notches 42 and the mere act of pushing the fuses 39 into position in the channels 34 causes them to be mounted in electrical contact with the clips 40 and 41.

The end walls 31 at the other ends of the channels 34, are formed with smaller semi-circular notches 43 which combine, when the body halves 30^a are brought together, to form small circular holes. The small circular holes are provided so that the end of a rod-like ejector, illustrated by the dot and dash lines 44 in Fig. 2, can be inserted therethrough to be used for pushing burnt out fuses 39 from the body 30 through the circular openings formed by the notches 42. In Fig. 2, one of the fuses 39 is illustrated in a partially ejected position. A small nail, a bobby pin, the tine of a fork or any other similar article can be used as a rod-like ejector. On the other hand, the receptacle could be supplied with an elongated wooden stick which could be used as a rod-like ejector.

The clips 41 are bent from strips of resilient conductive metallic material and have intermediate portions engaged about elongated plug-in bars 45. The plug-in bars 45 are shaped from rigid conductive metallic material and have end portions projected from the end walls 32 of the hollow body 30 for insertion into the receiving openings of a conventional electric outlet receptacle. The intermediate portions of the clips 41 are secured to the inner ends of the plug-in bars 45 by spot welding, riveting or in any other similar manner. The ribs 33, in lateral alignment with the clips 41 and inward thereof, are formed with aligned recesses 46 into which the intermediate portions of the clips 41 are extended. The intermediate portions of the clips 41 have a snug fit within the recesses 46, see Fig. 2, so as to retain the plug-in bars 45 against possible longitudinal movement with relation to the body 30.

The intermediate portions of the plug-in bars 45 pass through aligned notches 47 formed in the end walls 32. The inner ends of the plug-in bars 45 which extend beyond the intermediate portions of the clips 41 are fitted into complementary notches 48 formed in the ribs 33. Engagement of the plug-in bars 45 with the notches 47 and 48 in addition to retaining the bars against possible lateral displacement, also functions to retain the clips 41 concentrically in position within the channels 34 to receive the fuses 39.

The clips 40 which are fashioned from a blank similar to that shown in Fig. 6, are bent to the desired shape from a single piece of flexible conductive metallic material having substantially the shape of a cross. The arms of the cross-shaped pieces of material are bent to form the clips 40 which are circular in cross-section. One end of the bar portion of each of the cross-shaped pieces of material forms a tail portion 49 and has its free end bent into a semi-circular anchor portion 50 faced with its open side toward the respective fuse 39. The other end of the bar portion of each of the cross-shaped pieces of material is doubled back upon itself forming a conductive strip portion 51. As best shown in Figs. 2 and 5, the conductive strip portions 51 are angled away from the adjacent faces of the tail portions 49.

The ribs 33 inward of the channels 34 and the respective clips 40 are formed with elongated recesses 52 which are spaced from the channels 34 by intermediate walls 53. The walls 53 in alignment with the clips 40 are formed with cutouts 54 through which the intermediate portions of the clips 40 pass so that the clips 40 can be located within the channels 34 with the tail portions 49 and the conductive strip portions 51 located within the recesses 52. The ends of the walls 53 remote from the end walls 31 are formed with inwardly extended semi-circular lugs 55 about which the semi-circular anchor portions 50 of the tail portions 49 are engaged, as best shown in Fig. 2. The ribs 33 are formed with small projections 56 which abut the semi-circular anchor portions 50 retaining them rotatively in engagement with the semi-circular lugs 55.

The end walls 31 of the hollow body 30 are formed with notches 57 which continue from the outer ends of the recesses 52. The notches 57, when the body halves 30^a are brought together form passages through which the ends of the plug-in bars of a conventional plug can be passed into the recesses 52 to make electrical contact with the conductive strip portions 51. The conventional plug referred to is that type of plug which is commonly mounted on the end of an electric cord of conventional electrical appliances or devices; such as clocks, toasters, radios, television sets, irons, and the like. Thus, it will now be appreciated that the receptacle of the present invention is to be inserted between the conventional outlet receptacle for electric current and the plug of common electrical appliances so that the fuses mounted in the receptacle will function to provide complete protection for the electrical appliance or device with which it is connected.

Means is provided for turning the semi-circular anchor portions 50 about the semi-circular lugs 55 for holding the strips portions 51 in position to make good electrical contact with the plug-in bars of the inserted plug and for holding the clips 40 concentrically in position within the passages 34 to receive the fuses 39. The turning means comprises a transversely extended flexible anchor plate 58 fitted into opposed complementary grooves 59 formed in the adjacent faces of the body halves 30^a. The grooves 59 are located at the ends of the recesses 52 so that the one face of the anchor plate 58 bears against the free ends of the semi-circular anchor portions 50. When the anchor portions 50 are not engaged by the anchor plate 58, they have a natural bias, as shown in Fig. 5, so that their free ends stand away from the lugs 55. However, when the anchor plate 58 is in position it tends to compress the ends of the semi-circular anchor portions 50 against the lugs 55 causing the anchor portions 50 to turn about the lugs 55. As a result, the clips 40 and the strips portions 51, as viewed in Fig. 2, will be moved as a unit with the right hand ones turning in a counterclockwise direction and the left hand ones turning a clockwise direction. Such movement will cause the strip portions 51 to bear with good electrical contact against the adjacent faces of the inserted plug-in bars and maintain the clips 40 concentrically in position within the channels 34.

The anchor plate 58 is stamped from a thin sheet of dielectric material which preferably is fiber or the like material. It is also appreciated, that when the anchor plate 58 is in position, as shown in Fig. 4, it assists in retaining the body

halves 30^a against pivoting about the nut and bolt assembly 36.

From the foregoing description, it is apparent that the present invention provides a convenient fused receptacle which can be used for protecting any type of electrical appliance or device having a plug for insertion into a conventional outlet receptacle. The fused receptacle of the present invention is characterized by the fact that it may be quickly disconnected from the appliance or device with which it is being used and connected to another without using any tools or requiring any skill. A feature of the present construction resides in the fact that the ends 10 walls 31 and 32 of the body halves 30^a are especially thin with the overall length of the body 30 being not much greater than the length of the 15 contained fuses 39 so that little movement of the fuses is required for removing the same or inserting new ones.

In the modification of the invention shown in Figs. 9 to 11, the construction of the fused receptacle is characterized by the fact that the tail portions 49' of the clips 40 are of straight elongated formation. Those tail portions 49' are extended flush along the adjacent faces of the walls 53 and have their free ends fitted snugly into notches 60 formed in the rib 33 at the adjacent 20 ends of the recess 52'.

30 In all other respects, the form of the invention shown in Figs. 9 to 11 is similar to that previously described and like reference numerals are used to identify like parts.

The modification of the invention shown in 35 Figs. 12 to 14, is characterized by the fact that the fused receptacle is designed to receive the plug-in bars of an electric cord or cords at both of its ends. The fuses 39 are engaged at their 40 ends by clips 40' similar in construction to the clips referred to in connection with the description of the form of the invention shown in Figs. 9 to 11. At each end, the body halves 30^a are formed with recesses 52' which house the tail portions 49' and the conductive strip portions 51 of the clips 40'. Each of the end walls 31' and 45 32' is formed with the aligned notches which extend from the outer ends of the recesses 52' to admit the plug-in bars of the plugs.

The fused receptacle of Figs. 12 to 14 is constructed to be inserted between the adjacent ends of a severed cord of an electric appliance or device. Conventional push-in plugs are mounted on the severed ends of the cord for insertion into the fused receptacle from opposite ends thereof for providing protection for the appliance or device.

50 In all other respects, the form of the invention shown in Figs. 12 to 14 is similar to that described in connection with Figs. 9 to 11 and like reference numerals identify like parts.

60 Referring now to the modification of the invention shown in Figs. 15 to 17, the clips 48^a on opposite ends of the fuses 39 adjacent the end wall 31^a and 32^a are formed with metallic extensions 70. The extensions 70 are projected into complementary recesses 71 formed in the adjacent faces of the ribs 33^a. Each of the extensions 70 carries an attaching screw 72.

The body halves 30^a are alike in construction 70 differing only in the fact that the one half is formed with a centrally located hole 73 through which the end of an electric cord 74 is projected into the hollow body 30. Extended in opposite directions from the hole 73 to the recesses 71, the adjacent faces of the ribs 33^a are formed with

passageways 75 through which the individual leads of the cord 73 are extended to the respective extensions 78. The ends of the leads of the cord 73 are attached to the extensions 78 by means of the screws 72.

The body halves 30^a in this form of the invention are secured together by means of two sets of nut and bolt assemblies 36^a projected through complementary aligned apertures 35^a extended through the ribs 33^a outward of the recesses 71.

In all other respects, the form of the invention shown in Figs. 15 to 17 is also similar to that described in connection with Figs. 9 to 11 and like reference numerals identify like parts.

In the modification of the invention shown in Figs. 18 to 20, the clips 40^b are located adjacent the end wall 32^b of the hollow body 30. The clips 41^b are located adjacent the end wall 31^b of the hollow body and are constructed to include extensions 80 positioned within complementary aligned recesses 81 formed in the adjacent faces of the ribs 33^b. The extensions 80 are each provided with a single attaching screw 82.

The halves of the body 30 are alike in formation and the end walls 31^b, between the notches 43, are formed with aligned passages 83 through which a cord 84 enters the hollow body 30. Within the ribs 33^b, the passages 83 continue into aligned branch passages 85 which communicate with the recesses 81. The individual leads of the cord 84 are extended through the branch passages 85 and into the recesses 81 where they are connected to the extensions 80 by means of the attaching screws 82.

Again, the form of the invention shown in Figs. 18 to 20 is similar to that described in connection with Figs. 9 to 11 and like reference numerals are used for identifying like parts.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said hollow body having opposed halves of semi-elliptical shape so that said body is elliptical in transverse cross-section, and finger grip portions formed on the outer faces of said halves.

2. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall.

3. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said hollow body having opposed halves of semi-elliptical shape so that said body is elliptical in transverse cross-section, and finger grip portions formed on the outer faces of said halves,

said finger grip portions comprising inwardly sloped cavities formed in the outer faces of said body halves, and ridges bounding said cavities about their deep sides.

4. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said hollow body having opposed halves of semi-elliptical shape so that said body is elliptical in transverse cross-section, and holes formed in the other of said end walls aligned with said channels through which an ejector rod can be inserted for pushing said fuses from said channels through said openings, said openings and holes being formed by aligned semi-circular notches formed in the adjacent edges of the end walls of said body halves.

5. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extending laterally inward from said clips, and conductor members extended from said clips into said recesses, said hollow body having opposed halves of semi-elliptical shape so that said body is elliptical in transverse cross-section, and holes formed in the other of said end walls aligned with said channels through which an ejector rod can be inserted for pushing said fuses from said channels through said openings, said body being of a length

just slightly greater than the length of said fuses so that said end walls are very thin requiring a movement of said fuses just slightly greater than the length thereof for removing and inserting the same.

6. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall.

7. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall.

of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall, said conductor members of the other pair of clips at the other end of the hollow body comprising tail portions and conductive strip portions integral with said clips and extended into the respective recesses, said respective recesses being separated from said channels by walls along which said tail portions extended, said strip portions being angled away from the adjacent faces of said tail portions, the end wall at the said other end of said hollow body having holes for the passage of plug-in bars into said respective recesses to make electrical contact with said conductive strip portions.

7. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall, said conductor members of the other pair of clips at the other end of the hollow body comprising tail portions and conductive strip portions integral with said clips and extended into the respective recesses, said respective recesses being separated from said channels by walls along which said tail portions extended, said strip portions being angled away from the adjacent faces of said tail portions, the end wall at the said other end of said hollow body having holes for the passage of plug-in bars into said respective recesses to make electrical contact with said conductive strip portions, semi-circular anchor portions formed on the ends of said tail portions, semi-circular lugs formed on said walls and about which said semi-circular anchor portions extend, and projections within said hollow body engaging and maintaining said semi-circular anchor portions in contact with said lugs.

8. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall, said

conductor members of the other pair of clips at the other end of the hollow body comprising tail portions and conductive strip portions integral with said clips and extended into the respective recesses, said respective recesses being separated from said channels by walls along which said tail portions extended, said strip portions being angled from the adjacent faces of said tail portions, the end wall at the said other end of said hollow body having holes for the passage of plug-in bars into said respective recesses to make electrical contact with said conductive strip portions, semi-circular anchor portions formed on the ends of said tail portions, semi-circular lugs formed on said walls and about which said semi-circular anchor portions extend, and projections within said hollow body engaging and maintaining said semi-circular anchor portions in contact with said lugs, and means turning said semi-circular anchor portions about said semi-circular lugs for holding said strip portions in position to bear rigidly with good electrical contact against the plug-in bars inserted into said respective recesses and to maintain the respective clips concentrically in position within said passages.

9. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall, said conductor members of the other pair of clips at the other end of the hollow body comprising tail portions and conductive strip portions integral with said recesses being separated from said channels by walls along which said tail portions extend, said strip portions being angled away from the adjacent faces of said tail portions, the end wall at the said other end of said hollow body having holes for the passage of plug-in bars into said respective recesses to make electrical contact with said conductive strip portions, semi-circular anchor portions formed on the ends of said tail portions, semi-circular lugs formed on said walls and about which said semi-circular anchor portions extend, and projections within said hollow body engaging and maintaining said semi-circular anchor portions in contact with said lugs, and means turning said semi-circular anchor portions about said semi-circular lugs for holding said strip portions in position to bear rigidly with good electrical contact against the plug-in bars inserted into said respective recesses and to maintain the respective clips concentrically in position within said passages, said turning means comprising a flat resilient anchor plate set into grooves formed in said rib to bear against the free ends of said semi-circular anchor portions.

10. A fused electric receptacle comprising a hollow body having end walls, an integral rib extended between said end walls dividing off spaced channels for mounting cartridge fuses, a pair of clips within each of said channels at the ends thereof, and engaged with said fuses, there being

openings in one of said end walls aligned with said channels through which fuses can be pushed into said channels into electrical contact with said clips, said rib having recesses extended laterally inward from said clips, and conductor members extended from said clips into said recesses, said conductor members of one pair of clips at one end of said hollow body comprising plug-in bars extended from the respective recesses and through the respective end wall, said conductor members of the other pair of clips at the other end of the hollow body comprising tail portions and conductive strip portions integral with said clips and extended into the respective recesses, said respective recesses being separated from said channels by walls along which said tail portions extended, said strip portions being angled away from the adjacent faces of said tail portions, the end wall at the said other end of said hollow body having holes for the passage of plug-in bars into said respective recesses to make electrical contact with said conductive strip portions, said tail portions being straight and having their ends extended into complementary holding notches.

11. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clip, said rib having recesses extended laterally inward from said clips, and conductor members extended from said clips into said recesses, said conductor members of all of said clips being alike in construction with each having a tail portion and a conductive strip portion integral therewith and extended into the respective recess, said recesses being separated from said channels by walls along which said tail portions extend, said strip portions being angled away from the adjacent faces of said tail portions.

12. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of all of said clips being alike in construction with each having a tail portion and a conductive strip portion integral therewith and extended into the respective recess, said recesses being separated from said channels by walls along which said tail portions extend, said strip portions being angled away from the adjacent faces of said tail portions, said end walls of said hollow body having holes for the passage of plug-in bars of conventional plugs, into said recesses to make electrical contact with said conductive strip portions.

13. A fused electric receptacle comprising a hollow body having end walls, an integral rib extended between said end walls dividing off spaced channels for mounting cartridge fuses, a pair of clips within each of said channels at

the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of all of said clips being alike in construction with each having a tail portion and a conductive strip portion integral therewith and extended into the respective recess, said recesses being separated from said channels by walls along which said tail portions extend, said strip portions being angled away from the adjacent faces of said tail portions, said end walls of said hollow body having holes for the passage of plug-in bars of conventional plugs, into said recesses to make electrical contact with said conductive strip portions, said tail portions being straight and having their free ends projected into notches formed within said hollow body.

14. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, said conductor members of all of said clips being alike in construction with each having a tail portion and a conductive strip portion integral therewith and extended into the respective recess, said recesses being separated from said channels by walls along which said tail portions extend, said strip portions being angled away from the adjacent faces of said tail portions, and extensions from the clips located at opposite ends of said fuses, said extensions being located within complementary recesses formed in said hollow body, and means permitting the leads of an electric cord to be extended into said hollow body to be connected to said extensions.

15. A fused electric receptacle comprising a hollow body having end walls, an integral rib extended between said end walls dividing off spaced channels for mounting cartridge fuses, a pair of clips within each of said channels at the ends thereof, and engaged with said fuses, there being openings in one of said end walls aligned with said channels through which fuses can be pushed into said channels into electrical contact with said clips, said rib having recesses extended laterally inward from said clips, and conductor members extended from said clips into said recesses, and extensions from the clips located at one end of said body, said extensions being located within complementary recesses formed in said hollow body, and means permitting the leads of an electric cord to be extended into said hollow body to be connected to said extensions.

MAX J. MARCUS.
